GOVERNING MECHANISM

John A. Hess, Columbus, Ohio

Original application November 2, 1938, Serial No. 238,298, now Patent No. 2,194,166 dated March 19, 1940. Divided and this application November 7, 1939, Serial No. 303,208

3 Claims. (Cl. 287—92)

This invention has reference to governor mechanism of the type responsive to speed variations of a centrifugal device in turn controlling the admission of motive medium to a turbo-generator unit.

More specifically, the present invention is a division from my prior U. S. application for patent filed November 2, 1938, and which later matured into Patent No. 2,194,166, dated March 19, 1940, and the instant improvements have reference to a novel form of coupling connection between the pivotal lever arm, remote from its fulcrum, and the motive fluid valve stem, the primary object being to effectively prevent any 15 sidewise or vibratory motion between the parts aforesaid.

Another object is the provision of a novel coupling connection of the specified character which obviates undesirable wear between the 20 coupled parts, with a co-related effect upon the valve movable member relative to the valve body portion.

With the above recited and subsidiary objects in view, as well as ancillary advantages, this 25 invention comprises certain novel items of construction, and the combination and arrangement of parts, such as are set forth with particularity in the following description, when considered in conjunction with the accompanying sheet of drawings, and as more concisely expressed in the concluding claims.

In the drawing:

Fig. I is a broken elevational view through the governing mechanism end of a turbo-generator, and associated motive fluid valve, showing the improved coupler means of this invention included therein.

Fig. II is a vertical section on the plane II—II of Fig. I.

Fig. III is an enlarged perspective view of a 40 valve yoke housing included in the coupler means of this invention; and,

Fig. IV is a perspective view of a floating contact coactive with the housing of Fig. III, as hereinafter fully explained.

In the following disclosure considered in conjunction with the drawing, corresponding reference characters are applied to similar parts, while specific terms are employed for the sake of clarity. 45 It is to be understood, however, that such terms are non-limitatively used, but are intended to include all technical equivalents serving to accomplish an analogous purpose.

Referring more in detail to the drawing, and 50 by way of better clarifying the present improve-

ments, the reference character 5 comprehensively designates the governor portion of a standard type turbo-generator unit for locomotives, 6 the casing and 7 the cover component. The rotary bearing is indicated at 8, the same being suitably 5 attached to the unit armature-shaft 9, while 10 generally designates the governor, and 11 the stem thereof, which coacts with the conventional lever arm 12, said lever arm being pivotally suspended at 13 from an adjuster element 14 10 carried by a projection 15 in the unit casing 6; while the lever arm 12 is provided with a tongue 16, all preferably as set forth in the prior application hereinbefore referred to.

In accordance with the present improvements 15 and to provide a positive coupler-operating connection between the lever arm tongue 16, and the stem 17 of the motive fluid supply valve 18, said tongue is appropriately shaped for coaction between the opposing and preferably elliptic-section parts 19 of a yoke 20, having an internally 20 screw-threaded section 21 at one end adapted for adjustable and rigid attachment to the correspondingly-threaded end of the inwardly-influenced valve piston 22, for example as by a cotter 25 device 23.

It will also be seen the yoke 20 other end is 30 interiorly screw-threaded for reception of a hollow cap 24, having a concaved axial recess 25, affording bearing for the outer convexed end 26 30 of a floating contact member 27. This floating member 27, as best seen in Fig. IV, preferably embodies axially-aligned opposingly-directed stud-like portions 28, 29, respectively, of differential diameter, and an intermediate collar section 30. The stud part 28 embodies the hemispherically convexed end 26 engageable in the concaved recess 25 of the cap 24, and the part 29 freely passes through an axial aperture 31, and has a convexed end 32 of greater curvature 40 than the end 26 for contact with the tongue 16 or lower extremity of the lever arm 12. Thus it will be readily understood that the inner end or stud part 29 of the floating member 27 is 45 free to move laterally within certain limits, defined by the diameter of the aperture 31, hence a reasonable amount of sidewise vibration of the lever arm 12 can be absorbed without appreciable wear and without transmission of such vibrations to the valve piston stem 17. It will also 50 be obvious that the fluid supply valve stem 17 being inwardly influenced, maintains the lever arm 12 in constant contact with the governor stem 11, while the mechanism is operating.

From the foregoing it will be readily appar- 55

ent that by the improved coupling connection of this invention, between the lever arm 12 and the valve stem 17 is accurate and sensitive in operation, and that it substantially eliminates vibratory transmission between said parts.

Having thus described my invention, I claim:

- 5 1. The combination of a coupler connection for a governor influenced pivoted lever and the stem of a motive fluid supply valve comprising a 10 yoke device adjustably sustained by the valve stem, means for securing the yoke device at the desired adjustment, a cap fitting the yoke device, and a floating member afforded bearing at one end by said cap and oscillatably contacting the lever remote from its pivot at the other end, and means within the yoke member restricting sidewise movements of the lever to defined limits or without transmission thereof to the valve stem.
- 15 20 2. The combination of claim 1 wherein the

yoke device embodies an internally screw-threaded portion with diametrically opposed elliptic sections bridged by a suitable attaching means, the cap fits the screw-threaded section and is provided with a concaved interior axial recess, 5 and said yoke-device also includes an inner wall with a central aperture to define the lateral movement limits of the floating member.

3. The combination of claim 1 wherein the floating member embodies axially aligned stud-like portions with an intervening collar section, said stud-like portions being of differential diameters, the smaller of which has its free end rounded for conformatory engagement in the yoke member bearing cap, and the larger diameter stud-like portion free end is suitably convexed for oscillatory contact with the lever arm confronting end portion.

JOHN A. HESS. 20
